(57) CLAIM

The ornamental design for a horned toad shaped pet treat, as shown and described.

DESCRIPTION

FIG. 1.1 is a front perspective view of a Horned Toad Shaped Pet Treat showing my new design;

FIG. 1.2 is a front view thereof;

FIG. 1.3 is a rear view thereof;

FIG. 1.4 is a left side view thereof;

FIG. 1.5 is a right side view thereof;

FIG. 1.6 is a top plan view thereof;

FIG. 1.7 is a bottom plan view thereof.

The broken lines in FIG. 1.7 depict portions of the Horned Toad Shaped Pet Treat that form no part of the claimed design.
